WASHING MACHINE

David A. Meeker, Troy, Ohio, assignor to The Hobart Manufacturing Company, Troy, Ohio, a corporation of Ohio

Application October 12, 1934, Serial No. 748,003

22 Claims. (Cl. 141—9)

This invention relates to washing machines.

One of the principal objects of the invention is the provision of a washing machine of simple and compact construction, in which the articles to be washed may be readily inserted within and withdrawn from the machine.

Another object of the invention is the provision of a washing machine having a casing, and a movable cover member which is adapted to effectively retain the washing fluid within the casing during operation, and is adapted to be readily moved to an open position substantially within the horizontal confines of the casing to permit access thereto.

Another object of the invention is the provision of a washing machine of this character having simple and effective means for supporting racks or other articles within the casing while permitting the cover to be moved within the casing to positions beneath the rack supporting means.

Another object of the invention is to provide a washing machine of this character having a pivoted cover adapted to be readily rocked to positions permitting access to either of opposite sides of the casing.

Other objects and advantages of the invention will be apparent from the following description, the accompanying drawings and the appended claims.

In the drawings, which disclose preferred embodiments of the invention—

Fig. 1 is a vertical sectional view of a washing machine constructed in accordance with this invention;

Fig. 2 is a plan view of the machine illustrated in Fig. 1; the cover member being partly removed for clearness of illustration;

Fig. 3 is a fragmentary vertical sectional view taken on the plane of the line 3—3 of Figs. 1 and 2;

Fig. 4 is a vertical sectional view of a somewhat modified form of washing machine of this character;

Fig. 5 is a plan view of the machine illustrated in Fig. 4; the cover member being partly removed for clearness of illustration;

Fig. 6 is a fragmentary vertical sectional view taken on the plane of the line 6—6 of Figs. 4 and 5; and

Fig. 7 is a sectional view of the trunnion as indicated at 7—7 of Fig. 2.

A washing machine of approved construction embodying the invention has an open-top tank containing washing mechanism and a support for the articles to be washed whose supporting sur-

face is located on the level with the upper edge of the tank. Above the tank is supported an open-bottom casing providing a chamber in which the articles to be acted upon by this washing mechanism are placed. To permit access to the washing chamber, this casing is so supported that it may be tilted to bring one of its edges well above the top of the tank, while, at the same time, the opposite edge of the casing moves downwardly into the tank so that the center of gravity of the whole casing is only slightly raised. It is, therefore, possible to tilt the casing with little effort, and no counter-balancing means are required.

To permit one edge of the casing to move down into the tank, I mount the support for the articles to be washed in the tank in such manner that it has a long overhanging end extending towards one edge of the tank under which an edge of the casing may move. I also select a washing mechanism which may be supported near the middle of the tank, and which is provided with overhanging portions under which the edge of the casing may be moved. A suitable washing mechanism of this class is the type usually known as a rotary wash arm.

The drawings, in which like characters of reference designate like parts throughout the several views thereof, illustrate in Figs. 1, 2 and 3 a washing machine of this character having an open top tank structure 10 suitably supported upon legs 11 and having a movable casing or cover member 12 which serves as a closure for the open top tank 10 and, when in closed position, cooperates therewith to provide an enclosed washing compartment. Rack supporting tracks 14 are provided within the tank, preferably at about the plane of the top edge 15, for the reception of trays or racks or similar containers for articles to be washed. Suitable washing heads are provided which are adapted to spray fluid jets upon the articles to be washed and, as shown, include a rotary wash arm 20 and rinse jets, one of which is shown at 21. The rotary wash arm consists of a hollow member provided with radial arms having nozzles, some or all of which may be inclined so as to cause rotation of the wash arm by the reaction force of water discharged from the nozzles.

The tank 10 comprises vertically extending end walls 22 and side walls 22', and an inclined bottom wall 23 so shaped as to direct the liquid contents of the tank into a sump 24 which may be formed as an integral part of the tank 10. At the junction of the sump 24 and tank 10 a suitable supporting ledge 25 is provided for the reception

of a removable strainer 26 having a perforate bottom member 27 for the collection of solid material dislodged during the washing operation. A suitable drain, such as the threaded outlet 28, is provided to which a pipe connection may be attached for draining away the washing or rinsing liquid. As shown, a stand pipe 30 is provided at the outlet 28 so that a proper level of washing liquid may be maintained in the sump 24 during washing operation. The stand pipe 30 is provided with a tapered end 31 snugly received within a tapered socket formed in the bottom wall of a sump 24 immediately above the threaded portion 28 for the ready attachment and detachment of pipe 30 and to provide a water tight joint to prevent the unintentional escape of washing liquid. The stand pipe 30 is provided at its upper end with an opening or overflow outlet through which water, grease, scum, and the like, may pass upon exceeding the predetermined desired level within the sump 24. The pipe 30 is formed with a baffle 32 spaced above the overflow outlet and providing a handle for the pipe.

A circulating pump 33 having suitable driving means, such as the motor 34, is provided for the circulation of washing liquid and actuation of the wash arm 20. As shown, one side of the tank structure 10 opposite sump 24 is left open, and the motor 34 and pump 33 are mounted within this space so that access is readily had thereto, the motor being supported upon a shelf 35 carried by the tank 10 and legs 11. The pump 33 is provided with a suction inlet 36 extending through an opening in the side wall of sump 24 into lower portion of the sump 24 through which, during actuation of the pump 33, washing liquid will be drawn for discharge through pump outlet 38. The suction inlet is formed with an attaching flange 36' adapted to be bolted in liquid tight relation about the opening through the sump wall. The upper portion of pump outlet 38 is flanged as indicated at 38' for attachment to the flanged end 39' of a pipe 39 extending through an opening in the lower inclined wall 23 of the washing compartment of the tank 10. Preferably bolts pass through flanges 38' and 39' and into a shouldered portion of wall 23 to close the opening through which pipe 39 passes. Mounted in pipe 39 and held in place by nut 41 is a rod 42 providing a bearing for supporting the wash arm 20. The upper end of pipe 39 communicates with a central opening in the rotary wash arm to provide passages for the flow of water from pipe 38 to the wash arm 20. During operation of the device, water is circulated by the pump from the sump to the wash arm where it is discharged at high velocity against the articles to be washed, drains from the tank into the sump, and is again recirculated by the pump.

The rinse arm 21 is preferably of rotary type generally similar to the wash arm 20 and, as shown, is pivotally supported at 43 from a pipe structure 44 which may be connected to a suitable source of supply of rinsing water.

To permit easy handling of the articles to be washed they are preferably placed within the machine in suitable racks such as illustrated at 45; these racks being of such size as to be readily received upon the track structure 14 of the washing machine. Suitable rack supporting tables or shelves shown at 46 are shown provided at substantially the level of the track structure so that the article carrying racks 45 may be moved easily, and without lifting, into and out of the washing machine. Suitable connecting brackets 47 may be provided, as shown, for supporting the tables

46 from the tank structure 10. As shown, the track structure 14 comprises rack supporting rails 50 which are preferably of angular cross section having horizontally extending portions 51 for the support of the racks or trays and upstanding portions 52 for the guidance of the racks. Suitable supporting means are provided for the track structure and are shown as vertically extending arms or uprights 54 suitably attached to the track members 50, as by means of rivets 55, and supported at their opposite ends 56 within projections 57 which are preferably formed integrally within the tank structure 10. The projections 57 are preferably of socket like form within which the portions 56 may be securely held for the support of the track structure 14, and from which they may be readily withdrawn when it is desired to remove the structure 14 from the machine, as for the purpose of cleaning it. The vertical supports 54, which are attached to the track structure near the middle of its sides, are offset, as shown more clearly in Fig. 3, from the side walls of the tank a sufficient distance to permit the sides of the tilting casing to enter between them and the side walls of the tank. At the same time, these supports 54 are near enough the sides of the tank to clear the wash arm. The rails 50 of the structure 14 are shown shorter in length than the width of the tank 10 so that a clearance space is provided between the ends of the members 50 and the upstanding walls of the tank for the passage of the cover member 12 of which a portion is adapted to be received within the tank when it is moved to open position. The vertically extending portion of the rinse pipe 44 is preferably arranged at the side of the tank intermediate the vertical planes passing through the spaced trunnion axes. This pipe as shown is within and adjacent the side wall of the cover member, and passes upwardly between the cover and the side rail 50.

The cover member 12 is preferably of approximate semi-cylindrical form and is shown substantially semicircular in cross section. The curved shell or circumferential portion 60 is provided with parallelly extending end portions 61 which merge gradually into the curved portion 60 to provide a structure of sufficient depth within the limited confines of the radius of the member 60. The cover structure is completed by parallel side walls 62. The shape of the cover member 12 is proportioned to serve as a deflecting surface so that jets of wash water striking the cover will be directed back against the articles being washed. Spaced sets of trunnions 63 are carried by the opposite side walls 62. The trunnions provide parallel axes which are preferably spaced an equal distance on opposite sides of a vertical plane extending longitudinally through the center line of the cover 12 and provide pivotal supports upon which the cover member 12 may be rotated to provide an opening at either of opposite ends of the machine. The cover member 12 is supported above the tank 10 by means of suitable bearing brackets 64 which are mounted on the tank 10. As shown, the brackets 64 comprise yokelike bearing seats 65 within which the trunnions may be received; the bearing seats being open outwardly and inwardly so that as the casing 12 is moved the one pair of trunnions 63 may rotate in the corresponding bearing seats 65 while the opposite pair 70 of trunnions may move upwardly in a curved path without interference from the supporting seats.

The cover mounting is such as to permit free cover movement without the objectionable noise of metal to metal impact upon closure. As shown, 75

particularly in Fig. 7, a trunnion 63 is constructed as a cylindrical stud 110 having an end flange 111 which is fixed to the cover side wall 62. Rotatably mounted on the stud 110 is a metal sleeve 112 which has on its outer surface a yielding material such as an encircling band of rubber 113. The rotatable part is held in place on the stud by provision of a washer 114 that is attached to the stud end by a screw 115. The washer is preferably somewhat smaller in diameter than the rubber band and, as shown, is substantially the same diameter as the metal sleeve. Free rotation is afforded by movement of the trunnion stud on the metal sleeve, and freedom from the noise of metal to metal impact upon closure of the cover is provided by engagement of the yielding rubber band with the trunnion support or bracket 64.

The cover 12 is provided with suitable handles 20 or grips 68 by which it may be moved. The handles 68, positioned at opposite ends of the casing portion 60, are provided with lugs 69 which, in open position of the cover member 12, are adapted to engage the lip 15 of the tank 10 to limit the movement of the cover member. The edges 25 of the tank and the edges of the cover member which are parallel to the tilting axis of the cover member are termed herein for purposes of description the "ends" of these respective parts, and the edges of the tank and cover member which are perpendicular to the tilting axis are termed the "sides"; but it is to be understood that this implies no limitation as to the dimensions or shape of these parts. The trunnions 30 63 are positioned so that as the cover member is moved to open position, the balance of weight, or center of gravity, of the cover member will be shifted to a position to the outside of the supporting trunnions 63 to maintain the cover member in open position.

Suitable limiting means are incorporated in the open ends of the bearing seats 65 to prevent movement of the cover 12 beyond the normal open positions determined by the lugs 68. As shown, the limiting means comprise curved latching recesses 72 which extend from opposite sides of the trunnion supporting members 64 and are so positioned that as the cover 12 rocks about one pair of trunnions as a pivot the opposite pair may move out of engagement with the bearing seats without resistance. Should the cover be thrown or pushed open with considerable force, such as would tend to cause the trunnions 63 to bodily move out of their bearing seats 65 about the point of engagement of the stop 68 with tank 10 as a pivot, such movement beyond the normal open position is restrained by engagement of the trunnions 63 within their latching recesses 72. In closed position the downwardly extending edges of the cover member 12, as designated by the numeral 73 for the end portions 61 and the numeral 74 for the side walls 62, extend within the open top of the tank 10, as defined by the lip 15, an amount sufficient to provide an effective seal against the passage of washing fluid during operation of the machine even though the cover member does not actually contact with the tank 10. As shown, the end portions 22 adjacent the lip 15 are flared outwardly at 75 to receive the edges 73 of the cover member. The configuration or curvature of the surfaces 75 is such that any water from the jets or splashed against the surfaces will be deflected into the tank and will not pass through the clearance opening between the edges 73-74 and the lip 15. When the cover member is moved from closed position to an open position, one of the ends 61 moves downwardly into the tank 10 while the opposite end 61 moves upwardly to provide an opening approximately equal to the height of the washing chamber as defined by the cover member in closed position. The end 61 that is received within the tank moves downwardly between the lip 15 of the tank and the adjacent overhanging end of the track 50, passes under the path of travel of the overhanging end of the wash arm 20, and comes to rest when the lug 69 contacts with the lip 15; the degree of opening being limited to avoid contact with the supporting members 54 of the track.

By providing a cover member with parallel spaced trunnions, which permit the cover member to open to either of opposite ends, articles to be washed may be inserted within the machine at one end and, after washing, may be readily removed from the opposite end of the machine by merely shifting the cover member 12. This arrangement of parts permits the washing machine to be installed against a wall of a room and requires for its installation a space substantially equal to the horizontal dimensions of the tank structure since the cover member, in open position, is received within the tank and stands substantially within the confines of the tank area. When it is desired to disassemble the machine, as for the purpose of cleaning it, the entire cover member 12 may be easily removed by merely lifting the trunnions 63 out of engagement with the yoke like supporting bearings 64. The track structure 14 and the strainer 26 may then be lifted out. Removal of the stand pipe 30 permits the sump 24 to drain so that the entire interior of the machine is then exposed and readily accessible.

Referring now to Figs. 4, 5 and 6, a machine is shown of a type which is adapted for use in restricted areas, such as when positioned with its back to a wall or in a corner of a room so that the interior may be reached from only one end. The machine is provided with a cylindrical open bottom casing or cover member 80 having an upper wall of substantially semi-circular cross section comprising a curved surface 81 and opposed parallel side walls 82 upon which are provided aligned trunnions 84 positioned to one side of a vertical plane extending through the longitudinal center line of the cover 80. Suitable brackets 86 are provided on the tank 10' for the pivotal support of the trunnions 84 and to permit the cover 80 to be moved from a closed position, in which the open top of the tank is enclosed, to a position providing an opening which is approximately equal to the height of the wash chamber as defined by the cover member when in closed position. As shown, the upper portion of the tank 10' is provided with a ledge 88 having a portion extending across the front end 22 of the tank, and continuing portions 88' which extend along opposite sides 22' of the tank to points short of the vertical plane passing through the trunnion axis. The upper surface of this ledge is below the top edge of the tank, and the bottom edge 89 of the cover in closed position lies just over the surface of the ledge, providing a substantially leak-proof construction about this portion of the tank and cover, and at the same time providing freedom of upward opening movement of this part of the cover. The portions 88' of the ledge along the sides of the tank terminate as shown at about the vertical plane of the trunnion 70 75.

axis, so that the rear end of the cover is permitted to freely move down into the tank. To the rear of the vertical plane passing through the trunnion axis, the open edge of the tank 10' is provided with an inturned flange 70 which, in closed position of the cover member, is engaged by an outwardly turned flange extension 71 of the cover member. The inturned flange 70 of the tank and the outwardly turned flange 71 of the cover member extend across the rear edge of these parts and thence forwardly to approximately the vertical plane passing through the trunnion axis. The overlapping of flanges 70 and 71 provides an effective seal between the tank and cover member to restrain the passage of washing liquid at this portion of the respective parts. A suitable handle 83 is provided on the cover member for convenience in moving the cover member. The trunnions 84 are so positioned and the curvature of the cover member portion 81 is so proportioned that as the cover member is moved to open position the balance of weight or center of gravity will move to a position beyond the trunnion pivot point so that the cover member will be maintained in open position and will be held in such position by engagement of the surface of the portion 81 with the inner surface of flange 70 of the tank 10'.

A rack supporting track structure 14' is provided and, like the structure 14, is readily removable. As shown, the track structure 14' comprises parallel horizontally extending rails 90 having upturned flanges 91 for the guidance of a rack 45 and is provided with a limiting rear flange 92 which limits the insertion of a rack to a position substantially central within the washing machine. The tracks 90 are preferably positioned at a level about or slightly above the plane of the open edge of the tank 10' so that racks may be inserted or withdrawn without the necessity of lifting them over the edge of the tank. A suitable shelf extension 97 may be attached to the tank structure of the machine and positioned at the level of the tracks 90 to aid in the handling of the dish carrying racks. The track structure 14' is shown supported by means of spaced members 94 that extend forwardly toward the front of the tank and terminate in end portions 95 that are telescopically received within suitable horizontal sockets 96 provided adjacent the ledge 88 at the rack receiving side of the tank, and by laterally projecting members 98 that extend from the opposite sides of the track structure and terminate in end portions 99 that are received by a downward interfitting movement within sockets or grooves 100 formed in the upper faces of the ledge portions 88'. The rack support is thus in the form of a cantilever having an overhanging rear end which permits free passage of the adjacent portion of the cover member down within the tank beneath this overhanging end of the support, and beneath the path of travel of the overhanging end of the wash arm. The side rails 90 of the rack supporting structure are spaced inwardly from the inner surface of the side walls of the tank so that the lower edges of the sides of the cover member fit within and between these rails and the side walls of the tank when the cover is in closed position. The track structure 14' may be readily disengaged from mounted position by vertical withdrawal of the members 98 from the supporting grooves 100 followed by a horizontal rearward movement of the structure 14' to disengage the members 94 from the sockets 96. The vertically extending portion of the rinse pipe 44 75 is preferably arranged as shown at the side of

the tank adjacent the vertical plane of the trunnion axis. This pipe extends upwardly within the side wall of the cover member, passing between the cover member and the side rail 90. The remaining parts of the washing machine are generally similar to corresponding parts described for Figs. 1, 2 and 3. 5

There is thus provided a washing machine of compact construction having an easily accessible washing compartment, and which is adapted for 10 installation in positions, such as against a wall, which permits efficient utilization of kitchen space. The cover member of the machine is so arranged that it may be opened to a position substantially equal to the height of the wash chamber, and is maintained in such position by its own weight while standing substantially within the floor area of the machine. Articles to be washed may readily be inserted within and withdrawn from the machine on an easily removable track 20 structure which is so positioned as to avoid interference with the cover member which, in open position, is adapted to be received within the casing. Simple and effective means are provided for retaining the washing fluid within the machine 25 during operation. A construction is provided which permits the machine to be readily disassembled for cleaning.

While the forms of apparatus herein described constitute preferred embodiments of the invention, it is to be understood that the invention is not limited to these precise forms of apparatus, and that changes may be made therein without departing from the scope of the invention which is defined in the appended claims. 30 35

What is claimed is:

1. In a washing machine, an open top tank, a pivotally mounted open bottom casing providing a unitary hollow cover member therefor, trunnions for said cover member, and cover supporting means for receiving said trunnions for pivotal movement therein and opening upwardly for free removal of the trunnions, said trunnions and said cover supporting means being positioned on opposite sides of said tank intermediate the 45 ends of the tank, said cover member being adapted to pivot as a unit about said trunnions to raise one end above the top of said tank and lower the remote end into the tank.

2. In a washing machine, an open top tank, an open bottom casing providing a unitary hollow cover member therefor, trunnions for said cover member, supporting means for said trunnions, said trunnions and supporting means being positioned on opposite sides of said tank intermediate the ends thereof and providing a pivotal axis for said cover member, said cover member being adapted to pivot as a unit about said axis to raise one end above the top of said tank and lower the remote end into the tank, said axis being positioned between a central vertical plane passing through the cover member and said remote end of the cover member to provide a path of movement for the cover member in which said first mentioned end travels through an arc of 65 greater radius than said remote end upon movement of the cover to an open position. 55 60

3. In a washing machine, an open top tank, an open bottom casing providing a unitary hollow cover member therefor, trunnions for said cover member, and supporting means for said trunnions, said trunnions and supporting means being positioned on opposite sides of said tank above the top thereof and offset intermediate the ends of said cover member from the central vertical 70 75

plane passing through said cover member, said cover member being adapted to pivot as a unit about said trunnions from a closed position to an open position in which the end thereof most distant from said trunnions is raised a substantial distance above the top of said tank and the opposite end extends a substantially less distance into said tank.

4. In apparatus of the character described, an open top tank, a pivotally mounted open bottom unitary cover member therefor, trunnions for said cover member, supporting means for said trunnions, said trunnions and supporting means being positioned on opposite sides of said tank intermediate a central vertical plane passing through said cover member and an end of the cover member, said cover member being adapted to be moved on said trunnions from a closed position to an open position in which the end thereof most distant from said trunnions travels in an arc of relatively large radius and is raised a substantial distance above the top of said tank and the opposite end moves through an arc of smaller radius and extends a substantially less distance into said tank.

5. In a washing machine, an open top tank, rack supporting means mounted therein at substantially the level of the open top of said tank, a unitary cover member therefor having substantial depth to receive in closed position a rack of articles to be washed carried by said rack supporting means, trunnions for said cover member, supporting means for said trunnions, said trunnions and supporting means being positioned on opposite sides of said tank intermediate a central vertical plane passing through said cover member and an end of the cover member, said cover member being adapted to swing on said trunnions from a closed position to a position in which the end thereof most distant from the trunnions is raised a substantial distance above the top of the tank to provide a space for the insertion into and removal from said washing machine of a rack containing articles and the cover member is maintained open by an over-balance of weight to one side of said trunnions, and the opposite end of said cover member extends a substantially less distance into said tank.

6. In a washing machine, an open top tank having substantially straight side walls and having end walls provided with outwardly flared portions at the top, article supporting means positioned within the horizontal confines of said tank and substantially at the level of the open top of the tank, a cover member for said tank, said cover member comprising a unitary open bottom structure, means supporting said cover member for pivotal movement in which one end is raised above the top of said tank and the opposite end moves downwardly into the tank, the lower edges of said cover member in closed position being received within the side walls and the outwardly flaring portions of the end walls of said tank, the ends of said cover member being spaced from said outwardly flaring portions of the tank end walls and said flaring portions extending outwardly at angles sufficient to permit the end of the cover member to move downwardly into the tank.

7. In a washing machine, an open top tank, a rotatable wash arm positioned within said tank, supporting means for said wash arm, article supporting means positioned within the horizontal confines of said tank, a pivotally mounted open bottom casing providing a unitary cover member for said tank, trunnions for said cover

member, supporting means for said trunnions, said trunnions and supporting means being positioned on opposite sides of said tank intermediate the ends of said cover member, said cover member being adapted to be moved on said trunnion supporting means from a closed position to an open position in which a portion of the cover member is received within said tank and beneath said wash arm and article supporting means.

8. In a washing machine, an open top tank, a pivotally movable cover member for said tank, several spaced sets of trunnions for said cover member providing several spaced parallel axes, supporting means for receiving said trunnions for pivotal movement therein and opening upwardly for free withdrawal of either of said sets of trunnions as the cover member is pivoted on the other set; said cover member being adapted to be moved upon either of said spaced sets of trunnions to provide an opening at either of the opposite ends of said tank.

9. In a washing machine, an open top tank, a pivotally movable cover member for said tank, several spaced sets of trunnions for said cover member, supporting means for said trunnions providing several spaced parallel axes positioned above the horizontal plane of the open top of the tank and at opposite sides of a central vertical plane passing through said cover member parallel to the axes, said cover member being adapted to be moved upon either of said spaced sets of trunnions to provide an opening at either of opposite sides of the tank.

10. In a washing machine, an open top tank, a pivotally mounted cover member for said tank, several spaced sets of trunnions for said cover member, supporting brackets for said trunnions providing several spaced parallel axes, said supporting brackets comprising hook shaped members so proportioned and arranged as to permit one set of trunnions to move out of their respective supporting brackets as the other set of trunnions is rotated within their respective set of bearing brackets, said hook shaped brackets having latching recesses for retaining the respective set of trunnions therein upon pivotal opening movement of said cover.

11. In a washing machine, an open top tank, comprising vertically extending side and end walls and a bottom wall, a rotatable wash arm positioned within said tank, supporting means for said wash arm, rack carrying means comprising tracks adapted to receive an article carrying rack thereon, said rack carrying means being positioned within the horizontal confines of said tank and terminating short of said end walls, supporting arms for said tracks, socket members on said tank for receiving the ends of said arms, a pivotally mounted open bottom cover member for said tank, trunnions for said cover member, supporting means for said trunnions, said socket members and trunnion supports being positioned on the sides of said tank extending parallel to the direction of the rack track, said trunnions and supporting means being positioned intermediate the ends of said cover member, said cover member being movable upon said trunnions from a position in which the open bottom of the cover member is received within the clearance space between the tank walls and the ends of the rack carrying means to an open position in which a portion of the cover member is received within the tank and beneath the wash arm and rack carrying means.

12. In a washing machine, an open top tank

- comprising side and end walls and a bottom wall, a rotatable wash arm positioned within said tank, supporting means for said wash arm, rack carrying means comprising tracks adapted to receive 5 an article carrying rack thereon, said tracks being positioned within the horizontal confines of said tank and terminating short of said end walls, supporting arms for said tracks, socket members within said tank for receiving the ends of said 10 arms, a pivotally movable open bottom cover member for said tank, several spaced sets of trunnions for said cover member, supporting means for said trunnions providing several spaced parallel axes therefor, said socket members and 15 trunnion supports being positioned on the sides of said tank extending parallel to the direction of the rack tracks, said trunnions and supporting means being positioned intermediate a central vertical plane passing through the cover 20 member parallel to said axes and each end of the cover member, said cover member being movable upon either of said spaced sets of trunnions from a position in which the open bottom of the cover member is received within the clearance space 25 between the tank walls and the ends of the rack carrying means to an open position at either of opposite ends of the tank in which a portion of the cover member is received within the tank and beneath the wash arm and rack carrying 30 means.
13. A washing machine having an open top tank, washing mechanism in the tank supported from the bottom of the tank and having an overhanging end, a support for the articles to be washed mounted in the tank substantially on a level with the upper edge of the tank and having an overhanging end, an open bottom casing mounted above the tank to provide a washing chamber enclosing articles on said support and 35 means supporting said cover member for tilting movement to raise one of its edges and move its opposite edge into the tank under the overhanging ends of the washing mechanism and the support.
14. In a washing machine, an open top tank, a support for the articles to be washed, located near the top of the tank, secured to the tank near its middle and having overhanging ends extending towards the opposite ends of the tank, an open bottom casing supported above the tank to provide a washing chamber enclosing articles on 40 said support and means supporting said cover member for tilting movement in either direction to an open position to permit access to the washing chamber and to bring its end edges into the tank below the overhanging ends of the support.
15. In a washing machine, an open top tank, a rotary wash arm mounted in the tank, a support 45 for the articles to be washed, said support comprising upright members secured in the tank near its bottom and adjacent to, but spaced from, the middle portions of the side walls of the tank, and track members mounted on said upright members and projecting beyond them towards the ends of the tank, an open bottom casing providing a washing chamber above said article support, means supporting said casing for tilting movement about an axis intermediate the casing 50 ends, said casing having curved end walls adapted to enter the tank below the rack carrying track members and flat side walls adapted to enter the tank between the side walls of the tank and the track members, said cover standing in the closed position with the bottom edge portion telescopically interfitting the tank exteriorly of the said track, and means supporting the cover for tilting movement to open position in which an end of the cover moves upwardly for access to the track and the opposite end of the cover moves downwardly within the tank and beneath the overhanging end of the track.
16. In a washing machine comprising a tank and a cover pivotally movable to a closure position with respect to said tank, a cover support comprising trunnion receiving means, and trunnions on the cover providing two pivot axes therefor and spaced for selective pivotal movement of the cover on either of the axes, said trunnions each comprising a stud fixed to and projecting from the cover, and a rotatable sleeve on the stud having a yielding surface layer receivable 5 in the cover support.
17. In a washing machine comprising a tank and a cover pivotally movable to a closure position with respect to said tank, a cover support comprising trunnion receiving means, and trunnions on the cover providing two pivot axes therefor and spaced for selective pivotal movement of the cover on either of the axes, said trunnions each comprising a stud fixed to and projecting from the cover, a metal sleeve rotatable on the 15 trunnion stud, and an encircling band of yielding rubber on the sleeve receivable in the cover support.
18. A washing machine comprising an open top tank, a rack carrying track standing at substantially the level of the tank top and positioned within and spaced from the tank side walls, supporting means for the track positioned remotely with respect to an end of the track and affording a cantilever overhang thereof, socket means on 20 the tank for reception of the track supporting means affording free upward withdrawal of the track and holding the supporting means to restrain tilting thereof upon application of a load to the overhanging end, an open bottom cover 25 adapted in the closed position to enclose a rack on the track, and means supporting the cover for tilting movement to an open position in which an end of the cover moves upwardly for access to the track and the opposite end of the cover moves 30 downwardly within the tank and beneath the overhanging end of the track.
19. A washing machine comprising an open top tank, a rack carrying track standing at substantially the level of the tank top and positioned 35 within and spaced from the tank side walls, supporting means for the track positioned remotely with respect to an end of the track and affording a cantilever overhang thereof, socket means on the tank for reception of the track supporting 40 means affording free upward withdrawal of the track and holding the supporting means to restrain tilting thereof upon application of a load to the overhanging end, an open bottom cover above the tank having curved end walls adapted 45 to enter the tank below the rack carrying track members and flat side walls adapted to enter the tank between the side walls of the tank and the track members, said cover standing in the closed position with the bottom edge portion telescopically 50 interfitting the tank exteriorly of the said track, and means supporting the cover for tilting movement to open position in which an end of the cover moves upwardly for access to the track and the opposite end of the cover moves downwardly within the tank and beneath the overhanging end of the track.
20. In a washing machine, an open top tank, an open bottom casing providing a unitary hollow cover member therefor, trunnions for said cover 55 member, supporting means providing fixed pivots for said trunnions, said trunnions and supporting means being positioned on opposite sides of said tank intermediate the ends thereof, said cover member being adapted to move as a unit 60

about said pivots to raise one end above the top of said tank and lower the remote end into the tank, said pivots being positioned between a central vertical plane passing through said cover member and said remote end of the cover member to provide a path of movement for the cover member in which said first mentioned end travels through an arc of greater radius than said remote end upon movement of the cover to an open position.

21. A washing machine comprising an open top tank, a rack carrying track standing at substantially the level of the tank top and positioned within and spaced from the tank side walls, supporting means for the track positioned remotely with respect to an end of the track and affording a cantilever overhang thereof, said track supporting means comprising an arm extending forwardly from the end of said track opposite to said overhanging end and a laterally extending arm positioned remote from both ends of the track, socket means on the tank for reception of the track supporting means affording free upward withdrawal of the track and providing for holding the supporting means to restrain tilting thereof upon application of a load to the overhanging end, an open bottom cover adapted in the closed position to enclose a rack on the track, and means supporting the cover for tilting movement to an open position in which an end of the cover moves upwardly for access to the track and the opposite end of the cover moves downwardly

within the tank and beneath the overhanging end of the track.

22. A washing machine comprising an open top tank having an internal ledge near the top of its front wall and the front portions of its side walls and an inturned flange at the top of its rear wall and the rear portions of its side walls, a rack carrying track standing at substantially the level of the tank top and positioned within and spaced from the tank side walls, supporting means for the track positioned remotely with respect to the rear end of the track and affording a cantilever overhang at said rear end thereof, socket means on the tank for reception of the track supporting means affording free upward withdrawal of the track and providing for holding the supporting means to restrain tilting thereof upon application of a load to the overhanging end, an open bottom cover having an outturned flange at its lower rear edge portions, said cover being adapted in the closed position to be received within the confines of said tank with its lower front edge portions resting adjacent said ledge and its flange engaging the flange on the tank to provide an enclosed washing chamber above the track, and means supporting the cover for tilting movement to an open position in which the front end of the cover moves upwardly for access to the track and the opposite end of the cover moves downwardly within the tank and beneath the overhanging end of the track.

DAVID A. MEEKER.

CERTIFICATE OF CORRECTION.

Patent No. 2,128,008.

August 23, 1938.

DAVID A. MEEKER.

It is hereby certified that error appears in the printed specification of the above numbered patent requiring correction as follows: Page 1, second column, line 20, for the word "moved" read move; page 2, second column, line 67, for "outwardly" read upwardly; and that the said Letters Patent should be read with this correction therein that the same may conform to the record of the case in the Patent Office.

Signed and sealed this 11th day of October, A. D. 1938.

Henry Van Arsdale

Acting Commissioner of Patents.

about said pivots to raise one end above the top of said tank and lower the remote end into the tank, said pivots being positioned between a central vertical plane passing through said cover member and said remote end of the cover member to provide a path of movement for the cover member in which said first mentioned end travels through an arc of greater radius than said remote end upon movement of the cover to an open position.

21. A washing machine comprising an open top tank, a rack carrying track standing at substantially the level of the tank top and positioned within and spaced from the tank side walls, supporting means for the track positioned remotely with respect to an end of the track and affording a cantilever overhang thereof, said track supporting means comprising an arm extending forwardly from the end of said track opposite to said overhanging end and a laterally extending arm positioned remote from both ends of the track, socket means on the tank for reception of the track supporting means affording free upward withdrawal of the track and providing for holding the supporting means to restrain tilting thereof upon application of a load to the overhanging end, an open bottom cover adapted in the closed position to enclose a rack on the track, and means supporting the cover for tilting movement to an open position in which an end of the cover moves upwardly for access to the track and the opposite end of the cover moves downwardly

within the tank and beneath the overhanging end of the track.

22. A washing machine comprising an open top tank having an internal ledge near the top of its front wall and the front portions of its side walls and an inturned flange at the top of its rear wall and the rear portions of its side walls, a rack carrying track standing at substantially the level of the tank top and positioned within and spaced from the tank side walls, supporting means for the track positioned remotely with respect to the rear end of the track and affording a cantilever overhang at said rear end thereof, socket means on the tank for reception of the track supporting means affording free upward withdrawal of the track and providing for holding the supporting means to restrain tilting thereof upon application of a load to the overhanging end, an open bottom cover having an outturned flange at its lower rear edge portions, said cover being adapted in the closed position to be received within the confines of said tank with its lower front edge portions resting adjacent said ledge and its flange engaging the flange on the tank to provide an enclosed washing chamber above the track, and means supporting the cover for tilting movement to an open position in which the front end of the cover moves upwardly for access to the track and the opposite end of the cover moves downwardly within the tank and beneath the overhanging end of the track.
